CLAIM

The ornamental design for a drive unit for a meat grinder, as shown and described.

DESCRIPTION

FIG. 1 is a perspective view of a drive unit for a meat grinder illustrating our new design.

FIG. 2 is a front-side perspective view of the drive unit for a meat grinder.

FIG. 3 is a rear-side perspective view of the drive unit for a meat grinder.

FIG. 4 is a right side view of the drive unit for a meat grinder.

FIG. 5 is a left side view of the drive unit for a meat grinder.

FIG. 6 is a front view of the drive unit for a meat grinder.

FIG. 7 is a rear view of the drive unit for a meat grinder.

FIG. 8 is a top view of the drive unit for a meat grinder; and,

FIG. 9 is a bottom view of the drive unit for a meat grinder. The broken lines in the drawings depict portions of the drive unit for a meat grinder that form no part of the claimed design. The broken lines in FIG. 1 also show the environment during use of the drive unit for a meat grinder.
